Primary Examiner — Susan Bennett Hattan*Assistant Examiner* — Brett Miller(74) *Attorney, Agent, or Firm* — WPAT, P.C., Intellectual Property Attorneys; Anthony King(57) **CLAIM**

The ornamental design for a bottom for a pot, as shown and described.

DESCRIPTION

FIG. 1 is a perspective view of a bottom for a pot, showing my new design;

FIG. 2 is a front view thereof;

FIG. 3 is rear front view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing that the bottom for a pot is assembled with a cylindrical wall to form a pot.

The broken lines in the drawings depict environmental subject matter only and form no part of the claimed design.
